Primary Examiner — Katie Jane Stofko(74) *Attorney, Agent, or Firm* — Parsons Behle & Latimer(57) **CLAIM**

The ornamental design for a potato piece, as shown and described.

DESCRIPTION

FIG. 1 is a perspective view of a potato piece showing the new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view thereof, taken along line 8-8 in FIG. 1.

The evenly-spaced broken lines in FIGS. 1-7 illustrate end portions of the potato piece that form no part of the claimed design. The dash-dot-dash broken lines in FIGS. 1 and 4-7 illustrate the boundary of the claimed design which forms no part thereof.

1 Claim, 3 Drawing Sheets(56)
